UNITED STATES PATENT OFFICE.

GEORGE PUHA, OF BUFFALO, NEW YORK.

PLOW.

1,009,439.

Specification of Letters Patent. Patented Nov. 21, 1911.

Application filed March 13, 1911. Serial No. 614,049.

To all whom it may concern:

Be it known that I, GEORGE PUHA, a subject of the King of Hungary, residing at Buffalo, in the county of Erie and State of 5 New York, have invented new and useful Improvements in Plows, of which the following is a specification.

This invention relates more particularly to wheel plows of the kind in which the plow 10 is pivoted to the beam and provided with means for raising and swinging it clear of the ground in moving the implement from place to place.

One of the objects of my invention is to 15 improve the implement with a view of simplifying the construction of the plow-raising mechanism and rendering it convenient in operation.

Another object is to provide simple and 20 reliable connecting means between the plow and the colter, whereby the colter is caused to follow the movements of the plow.

In the accompanying drawings consisting 25 of 2 sheets: Figure 1 is a sectional elevation of the improved plow. Fig. 2 is a top plan view thereof. Fig. 3 is a transverse section on line 3—3, Fig. 1, on an enlarged scale. Fig. 4 is a longitudinal section on line 4—4, Fig. 3. Figs. 5 and 6 are transverse sections 30 on the correspondingly numbered lines in Fig. 1.

Similar letters of reference indicate corresponding parts throughout the several views.

35 The front portion of the plow beam preferably consists of a single bar A, while its rear portion comprises a pair of spaced parallel bars A¹ riveted or otherwise secured to the front bar or section, as shown at a. The 40 front portion of this beam is supported upon a suitable truck comprising an axle B and wheels B¹, B².

C indicates the plow-body having an upward extension or front standard c pivoted 45 near its upper end to the rear portion of the plow-beam by a transverse pin c¹ to permit the body to swing lengthwise of the beam. At its lower rear end the plow body carries a roller or caster D upon which it is 50 supported when its front portion is raised clear of the ground in transporting the implement. This roller is swiveled in a bracket D¹ secured at one side to the adjacent heel of the plow and at its opposite 55 side to a brace d fastened at its front end to the back of the plow-share.

Extending upwardly from the rear portion of the plow-body is a rigid rear standard or rack-bar E the toothed portion of which is curved concentrically with the 60 pivot c¹ and is engaged by a gear-segment f mounted on a longitudinally-swinging hand lever F pivoted at f¹ between the rear sections A¹ of the plow-beam. The rear supporting wheel D rests normally upon the 65 ground, and upon pulling the hand lever F backwardly, the rear portion of the plow-beam is caused to rise on the rack bar E and at the same time the front portion of the plow swings upwardly to the position shown 70 by dotted lines in Fig. 1, thus raising the plow-body clear of the ground and permitting its easy transportation from place to place. Upon swinging the hand lever forwardly, the plow is lowered to the position shown by full lines in Fig. 1. This lever may be locked in position by any suitable means, the preferred devices shown in the drawings consisting of a notched segment g secured to the plow-beam and a co-operating locking pawl g¹ carried by the 75 lever.

At its rear end the plow-beam may carry the usual handles H for controlling the implement when used as a hand-plow. It is 80 also preferably provided with a removable driver's seat I, so that the implement may be used as a riding plow. In the construction shown in the drawings, the arm or shank i of the seat is provided at its lower 85 end with hooks or lugs i¹ which embrace a stem i² extending upwardly from the bracket D¹. This construction permits the seat-arm to be applied to said stem by simply slipping its hooked portion over the 90 same, and to be as readily detached therefrom when the seat is not desired.

J indicates the colter arranged above the plow-point in the customary manner. It is carried by a bracket or holder J¹ preferably 100 pivoted to the plow-beam by a transverse pin j, thus permitting the colter to swing lengthwise of the beam. A link k connects the upper end of the colter with the upper end of the front plow-standard c, the latter 105 and the colter shank extending above their pivots c¹ and j, as shown. By this connection, when the plow-body is raised clear of the ground, the upper end of the standard c is swung rearwardly, swinging the upper 110 portion of the colter in the same direction and its lower portion in a forward direction

to the position shown by dotted lines in Fig. 1. The colter while occupying the desired position relative to the plow-point in the normal operation of the implement, is by this construction caused to swing forwardly and upwardly with the plow-point when the plow is raised, keeping the colter out of contact with the plow-point at all times and preventing injury to the latter and the colter.

The colter is preferably capable of angular adjustment laterally or crosswise of the plow to suit different conditions or kinds of soil. When the ground is comparatively soft, it is desirable to set the lower end of the colter so as to incline toward the mold-board of the plow, while when the soil is hard or contains stones it is desirable to set the colter to incline in the opposite direction. In the construction shown in the drawings, the shank of the colter is arranged in upper and lower loops j^1 , j^2 of the holder J^1 and fitted therein in such manner that it is capable of rocking or inclining laterally, as indicated by dotted lines in Fig. 5. As shown in the last-named figure, the colter-shank is fitted somewhat loosely in the lower loop j^2 while the side-bars of the upper loop are spaced a considerable distance apart and carry transverse adjusting screws j^3 which bear against opposite sides of the colter shank. It is obvious that the angle of the colter can be readily adjusted as desired by turning one of these thumb screws forward and the other backward. The truck wheel B^1 located on the mold-board side of the plow is preferably of greater diameter than the other wheel B^2 and adapted to run in the furrows to serve

as a gage wheel toward and from which the front portion of the plow-beam is adjustable for regulating the space between the furrows.

L indicates an arch secured to the axle B and adjustably supporting the front portion of the beam A ; q the draft pole attached to the axle, and R forwardly converging draft-chains connecting the rear end of the pole with the outer end of a cross head S secured to the central portion of the plow-beam.

I claim as my invention:

1. The combination of a plow-beam, a plow-body having front and rear standards, said front standard being pivoted to the beam to swing longitudinally thereof, a supporting roller carried by the lower rear portion of the plow-body, and raising and lowering means engaging said rear standard.

2. The combination of a plow-beam, a plow-body having a standard pivoted to the beam to swing lengthwise thereof, a colter having a shank also pivoted to the plow-beam to swing lengthwise thereof, the colter-shank and said plow-standard extending above their pivots, a link connecting the upper ends of said standard and shank, and means under the control of the operator for swinging the plow-body into and out of operative position.

Witness my hand this 8th day of March, 1911.

GEORGE PUHA.
